ARTHUR HENRY BRYANT, OF EAST HARTFORD, CONNECTICUT, ASSIGNOR
OF ONE-HALF TO WILLIAM NAFEW HASKELL, OF ALBANY, NEW YORK.

KEEPER-RING FOR BUTTONS.

SPECIFICATION forming part of Letters Patent No. 740,353, dated September 29, 1903.

Application filed May 7, 1903. Serial No. 156,015. (No model.)

To all whom it may concern:

Be it known that I, ARTHUR HENRY BRYANT, a citizen of the United States, and a resident of East Hartford, in the county of Hartford and State of Connecticut, have invented a new and Improved Keeper-Ring for Buttons, of which the following is a full, clear, and exact description.

This invention relates to means for detachably holding shanked buttons upon garments, and has for its object to provide a novel keeper-ring for the purpose indicated which is shapely, very convenient to apply and remove, strong and durable, and that may be manufactured readily at low cost.

The invention consists in the peculiar conformation of the device from a single piece of resilient metal.

Reference is to be had to the accompanying drawings, forming a part of this specification, in which similar characters of reference indicate corresponding parts in all the figures.

Figure 1 is a side view of the improved keeper-ring. Fig. 2 is a perspective view of a button having a shank that is inserted through a flap of a garment, shown in section, and a side view of the improved keeper-ring, illustrating its initial engagement with the button-shank or the first step in the act of interlocking the ring therewith. Fig. 3 is a view similar to Fig. 2, showing the second step in effecting an interlocking engagement of the keeper-ring with the shank of the button. Fig. 4 is a side view of the button and its shank, a portion of the garment in section, through which the button-shank is inserted, and an edge view of the improved keeper-ring, showing its completed interlocking engagement with the button-shank; and Fig. 5 is an end view of the keeper-ring, showing the overlapped engagement of its locking members, seen in the direction of the arrow in Fig. 1.

The improved keeper-ring is preferably formed from a strand of resilient wire, having proper length and such thickness as will afford necessary rigidity in use. The wire strand is bent circularly at its longitudinal center to sufficient degree to produce a segmental ring 6, having sufficient diameter to afford efficient service, and preferably said segmental ring comprises three-fourths of a

full circle. Integral with the terminations of the segmental ring 6 two short straight members 7 are extended in the same plane therefrom and parallel with each other. Two similarly-curved members 8 are completing end portions of the open keeper-ring, these members projecting toward and lapping upon each other and in use serve to lock the shank of a button at a desired point on material the shank of the button has penetrated. The bodies of the curved members 8 are laterally flattened to give them wedge form, and thus adapt them to have a proper seated engagement with each other, the combined diameter of 65 said parts 8 being preferably greater than that of other portions of the keeper-ring, so as to insure strength thereby. The lapped members 8 together form the arc of a circle having less diameter than that of the segmental 70 ring 6, and, as shown in Fig. 1, the complete keeper-ring in normal shape is pear-shaped in contour—a conformation that is very advantageous, as will be apparent from the following description of the application of the 75 device.

The segmental ring 6, which is resilient and normally holds the lapped members 8 in assured contact with each other, is gripped edgewise between the thumb and front finger, as indicated by dotted lines in Figs. 2 and 3, when the keeper-ring is to be connected with the shank A' of a button A and that has been inserted through a suitable perforation in fibrous material B, whereon the button 85 is to be detachably secured, the button being held similarly by the same members of the other hand.

It will be evident that by slight compression of the opposite curved edges of the segmental ring 6 the locking members 8 will be moved across each other, thus causing their free end portions to project beyond the straight members 7. While maintaining pressure on the segmental ring 6 the person holding it 90 passes either of the ends a of the curved locking members 8 through the eye in the shank A' that has passed through the material B, so that at this first stage of the operation the relative positions of the engaged 95 member 8 and the button-shank will be as shown in Fig. 2.

It will be seen that if the keeper-ring is now rocked edgewise in the direction of the curved arrows $x x'$ in Figs. 2 and 3 and the button-shank A' rocked toward the remaining curved member 8 the latter will readily pass over the edge of the shank and assume the position thereon indicated in Fig. 3.

Obviously it is only necessary now to continue rocking the keeper-ring edgewise until the point of the locking member 8 that rests upon the shank A' clears said shank to permit the two curved locking members to assume normal positions of overlapping contact, whereupon the keeper-ring will be properly engaged with the button-shank and the button be thus secured upon the material B, as shown in Fig. 4.

When the improved keeper-ring is to be detached from the fabric, the segmental ring 6 is compressed edgewise, so as to expose the points a , and then either of these points is passed over the shank A', so that the curved members 8 assume relative positions on the shank shown in Fig. 3. It will now be seen that if the segmental ring 6 is rocked edgewise in the direction of the arrow x' in Fig. 3 the keeper-ring will be disengaged from the button-shank.

The operation of connecting and disconnecting the improved keeper-ring is extremely simple and easy to effect and can be executed readily and without close inspection.

The improvement is available for holding the shanks of buttons on any article of ap-

parel whereon detachable buttons are employed.

Having thus described my invention, I claim as new and desire to secure by Letters Patent—

1. A keeper-ring for buttons, comprising a resilient segmental ring, integral straight parallel members extended from terminations of the segmental ring, and curved laterally-projected locking members, said curved members being flattened into wedge shape and having lapped contact with each other.

2. The combination with a button-shank having an eye therein, of a keeper-ring, formed of a single piece of resilient wire, said ring having an essentially pear shape, comprising a segmental portion at one end thereof, two straight parallel members projecting from the segmental portion, and two wedge-shaped locking members curved laterally and lapping upon each other, either of said locking members being adapted for a free insertion into the edge of the button-shank when the segmental ring is compressed edgewise so as to project the ends of the locking members exterior of the straight members.

In testimony whereof I have signed my name to this specification in the presence of two subscribing witnesses.

ARTHUR HENRY BRYANT.
